FERRULE CRIMPING TOOL

Robert C. Swengel, Goldsboro, Pa., assignor to
Aircraft-Marine Products Inc., Harrisburg, Pa.,
a corporation of New Jersey

Application October 5, 1944, Serial No. 557,271

2 Claims. (Cl. 81—15)

1

This invention relates to crimping tools or the like and particularly to tools such as are employed for crimping the ferrules of terminal connectors upon the ends of electrical conductors. More particularly the invention relates to simple means for quickly adapting a crimping tool or the like for use with various sizes of wire or with varying ferrule diameters so as to prevent either insufficient engagement or weakening of the wire by over-compression in the operation of crimping the ferrule upon the end of the electrical conductor.

As more fully set forth in the copending application of U. A. Whitaker, Serial No. 455,039, filed August 17, 1942, and now abandoned, for Electrical connectors, a tool which has been set to compress a ferrule to a certain cross-sectional area on a given wire would compress a larger size ferrule on the same wire to such an extent as to weaken the wire by unduly reducing its cross section; whereas, with an undersize wire or ferrule, the compression might not be such as to achieve perfect results. It is, therefore, desirable that provision be made for quickly and easily adjusting the tool to obtain the desired crimping result with any set of conditions within a predetermined range.

A general object of the present invention, therefore, is to provide simple means (preferably operable by the hand which holds and operates the tool) for varying the limit of approach of the crimping dies to each other in the crimping operation, whereby, as above suggested, the tool may be quickly adjusted for different wire gauges or to different ferrule sizes, or to both. More particularly the invention aims to provide a stop which is movable into different positions between the jaws which carry the crimping dies so as to vary the amount of closing movement of these jaws.

In the illustrative embodiment of the invention the adjustable stop for varying the approach of the crimping die carrying jaws to each other is shown as incorporated in a crimping tool of the double lever type and an important feature of the illustrative embodiment of the invention is the mounting of the jaw stop on a slide guided on the link which ties together the crimping die jaws, this slide being so arranged that it may be engaged by the thumb of the tool operating hand and quickly and easily moved into any one of a plurality of predetermined stop positions.

Another important feature of the invention is the simple means by which the stop is yieldingly held in any one of its predetermined stop positions.

Other objects and important features of the invention to which attention has not specifically been directed hereinabove will appear from the

following description and claims when considered in connection with the accompanying drawings.

Although in the accompanying drawings I have shown a preferred embodiment of my invention and have described the same and suggested various modifications thereof in this specification, it is to be understood that these are not intended to be either exhaustive or limiting of the invention, but, on the contrary, are chosen for the purposes of illustrating the invention in order that others skilled in the art may so fully understand the invention, its principles and the application thereof, that they may embody it and adapt it in numerous forms, each as may be best suited to the requirements of its particular use.

In the drawings,

Figure 1 is a perspective view of a crimping tool of the double lever type having the adjustable stop of the present invention embodied therein, and with the ordinary handles broken away;

Figure 2 is a perspective detail showing the construction of the stop slide, with its thumb engaging part, as an integral sheet metal stamping;

Figure 3 is a transverse section on the line 3—3 of Figure 1;

Figure 4 is a fragmentary side elevation of a modified form with the spring holder shown in section; and

Figure 5 is a fragmentary plan view with a part of the stop slide broken away.

The crimping tool in which the stop means of the present invention is shown as embodied is of the general type more fully shown in the copending application of Uncas A. Whitaker, Serial No. 455,039, and is of the double lever type. In other words, the tool comprises handle levers 20 and 21 pivotally connected to each other at 40 and held with their hand-engaging long arms in separated relation by a spring 41. The jaw levers 24 and 25, which carry, or in which are formed, the crimping dies 26 and 27, are fulcrumed on a pivot 28 and pins 32 and 33, peened over at their upper and lower ends upon links 42 and 43 which serve to maintain the pivot pins 32 and 33 in a predetermined spaced relation to each other.

The long arms of the jaw levers 24 and 25 are pivotally connected at 38 and 39 to the short arms of the handle levers 20 and 21 respectively.

From the foregoing description it will be seen that when the handles are grasped by the hand of the operator and moved toward each other the pivots 38 and 39 will move away from each other and rock the jaws levers 24 and 25 about the pivots 32 and 33 to move the crimping dies 26 and 27 toward each other. If no stop be interposed between the jaws, the dies 26 and 27 will be moved toward each other until their flat faces actually abut at their tips 30—31. This will de-

termine the crimping action for the smallest gauge of wire and the smallest ferrule to be crimped thereon for which the tool is adapted. If, however, it be desired to use the tool with a larger gauger of wire and a ferrule of correspondingly larger diameter it is important, in order to prevent injury to the wire or to the ferrule, to stop the movement of the dies 26 and 27 short of this actual abutment. To this end the invention contemplates the provision of a stop that can be interposed between the jaws at a point or at different points on the jaw parts of the levers 24 and 25 between the crimping dies 26 and 27 and the outer edge or end of the link 42.

In the illustrative embodiment of the invention this stop 44 is shown as a downturned lug upon a slide 45 stamped up out of sheet metal and having a wider portion beyond the stop portion 44, this wider portion being, however, not sufficiently wide to prevent its sliding between the pivot pins 32 and 33. In stamping out the stop slide 45, as shown more particularly in Figure 2 of the drawings, the central portion thereof is stamped up to form a thumb piece 46 and the end of the slide is turned up at 47 to engage in parallel dents 48 formed in the spring holder 50 which is snapped onto the link 42.

To hold the slide 45 in operative relation and at the same time to permit its adjustment lengthwise of the link, a spring holder 50 is provided which, as shown in the sectional view, Figure 3, is provided with an opening 51 in its upper part to receive the thumb piece 46 and embraces the slide 45 by inturned snap flanges 52 and 53 on its sides which engage grooves 54 and 55 in the side of the link 42.

The rear end 47 of the slide 45 is formed to fit into the V-shaped or rounded grooves 48 in the holder 50 and the metal from which the holder 50 is formed should be sufficiently resilient so that it presses the slide 45 against the levers 24 and 25 that, when the operator pushes the thumb piece 46 in either direction, the spring holder 50 will yield resiliently to permit the end 47 to ride up out of the V-shaped depression 48 in which it may then be located and to travel into the next adjacent depression. The slide 44 is made of metal sufficiently strong to withstand the stress of this snap over with no permanent bending and only slight resilient bending. To improve this rigidity, I prefer to make the end 47 stamped out, as shown in Figure 2, rather than merely bending up the end.

In this manner the slide 45 may be moved to bring the stop 44 into different predetermined stop positions between the jaws 24 and 25. It will be obvious, of course, that the thumb engaging surface of the thumb piece 46 may be milled or knurled, etc., if desired, to insure proper gripping of the thumb piece 46 by the thumb.

Washers 49 between the jaw levers 24 and 25 and the link 42 provide the necessary spacing for the slide 45 under the link. It is also feasible to mount the slide above the link, stamping a suitable guiding recess 56 in the spring holder 50a, as shown in Figure 4. This arrangement, however, puts the slide 45a and the upper part of the lug 44a in a position more vulnerable to injury by ordinary handling of the tool. In the tool shown in Figure 4, a projection 47a is formed at one or both sides of the slide 45a and grooves 48a are formed in the surface of the link 42a. These serve as a detent under pressure of the spring 50a. Or the groove and projection can

be formed on the slide and spring holder 50a instead of on the slide and link, or in addition thereto.

If the jaws 24 and 25 had smooth inner faces between the dies 26 and 27 and the link 42, these faces would make a small angle in certain positions of the jaws when they close against the stop closer or farther from the vertex of the angle. There is advantage, however, in forming accurate stepped faces 58, 58', 58'', etc., one for each adjustment of the slide as shown in Figure 5, and these faces may be made at such angles respectively, that opposed faces are always parallel, or at the same angle to each other, when they engage the stop 44.

From the foregoing description it will be seen that simple means have been provided by the present invention for quickly and easily adapting a crimping tool for use with wires of different gauges and for use with ferrules of different cross-sectional dimensions.

I claim:

1. In a tool of the class described, the combination with pivoted die-carrying jaws having suitable operating handles connected thereto of a slide mounted for movement along a line within the angle determined by opposed faces of said jaws; said slide including a stop portion extending between said jaws and upon which the jaws may be closed to limit the extent of their approach toward one another, said jaws being pivoted respectively at spaced pivots on a relatively stationary member, said stationary member being provided with resilient means holding said slide against relative movement with respect thereto, and said resilient means and said slide including cooperating detents for holding said slide and stop portion in an adjusted position.

2. In a tool of the class described, the combination with pivoted die-carrying jaws having suitable operating handles connected thereto of a slide mounted for movement along a line within the angle determined by opposed faces of said jaws; said slide being a sheet metal stamping and including a flat slide portion having a tooth projecting from one side thereof, a central thumb piece stamped up from said flat portion and a stop portion bent down from said flat portion and projecting between the jaws of the tool, said jaws being pivoted respectively at spaced pivots on a relatively stationary member, said stationary member being provided with resilient means holding said slide against relative movement with respect thereto, and a series of depressions in said stationary member adapted to engage said tooth under pressure of the resilient means and sufficiently shallow to allow said tooth to move from one depression to another by resilient yielding of said resilient means.

ROBERT C. SWENGEL.
